UNITED STATES PATENT OFFICE.

CARL R. GRAVES, OF CLARION, IOWA.

HIGHWAY-CROSSING SIGNAL SYSTEM.

Application filed March 31, 1925. Serial No. 19,688.

To all whom it may concern:

Be it known that I, CARL R. GRAVES, a citizen of the United States, residing at Clarion, in the county of Wright and State 5 of Iowa, have invented certain new and useful Improvements in Highway-Crossing Signal Systems, of which the following is a specification, reference being had to the accompanying drawings.

10 This invention relates to means designed to be used at highway crossings for the purpose of causing a signal to be actuated as a train approaches the crossing and the signal to be shifted to its safety indicating position after the train has crossed the highway, and more particularly this invention relates to certain improvements or additions to the mechanism illustrated in the patent granted to me on August 26, 1924, 20 #1,506,630, and to means for causing the actuation of a signal such as that shown in my application Serial #7,072 filed on the 5th day of February, 1925, by mechanism located upon a siding as well as distinguished from mechanism located upon the main track.

The general object of the invention is to provide means whereby the said signal shall be actuated upon the approach of a train 30 upon the main track, whether this train enters the siding or crosses the highway upon the main track.

A further object is to provide means whereby a train may enter upon the siding 35 and after it has passed the highway restore the signal to its safety position, but that if this train returns along the siding or backs out of the siding so that it again crosses the highway it will again set the signal to danger position immediately upon backing and will restore that signal to its safety position after the train has passed the highway crossing.

A still further object is to provide a 45 mechanism operated by a train entering upon the siding and pulling out therefrom which will permit a train to pull in on the siding to wait for another train and while the train is standing on the crossing the signal will remain in danger position but that if it be necessary to cut the train for the highway crossing then when the last car where the cut is made has pulled up the last truck will put the signal in clear 50 position, the mechanism being such, however, that this will not prevent a train com-

ing in on the main line and passing the train on the siding operating the signal just as though there was no train on the siding and upon the departure of the train 60 on the main line this main line train will put the signal into clear or safety position, and further the mechanism being such that when the two sections of the train on the siding are moved to couple up again, the 65 wheels of the car where the cut was made will strike the actuating device which constitutes a combined setting and releasing or restoring lever and will set the signal to danger position, the signal remaining in 70 danger position until the last car clears the crossing, this mechanism acting, when the last truck of the train has passed, to put the signal into clear position.

Other objects will appear in the course 75 of the following description.

My invention is illustrated in the accompanying drawings, wherein:—

Figure 1 is a plan view of a main track and a siding at a crossing; 80

Figure 1^a is a plan view of the main track and the entrance to the crossing, Figures 1 and 1^a being intended to be read in connection with each other;

Figure 2 is a fragmentary perspective 85 view showing the operating rods and levers and a portion of the main track;

Figure 3 is a side elevation of a portion 90 of the main track showing the signal setting mechanism;

Figure 4 is a side elevation of a portion 95 of the main track showing the combined setting and restoring mechanism;

Figure 5 is a fragmentary perspective 100 view showing the connection between the rod 42 and the rod 67^b.

Referring particularly to Figures 1 and 1^a, it will be seen that these figures illustrate a highway crossing A, a main track B, and a siding C, both the siding and the main 105 track crossing the highway crossing A. Disposed in connection with the highway crossing is a signal post D having mounted thereon a signal such as is illustrated in my Patent #1,506,630 granted August 26, 1924, or such as is illustrated in my co-pending application Serial #19,689, filed on the 31st day of March, 1925.

It is not believed necessary to illustrate either of these signals in detail, it being 110 sufficient to say that the signal includes a mast D and a pivotally mounted signal

arm *d* carried thereby which, when it is raised, is in danger position and indicates the approach of a train and which, when it is lowered, is in a clear or safety position and indicates that the train has passed and that one may cross the tracks without danger. In connection with the main track there is disposed, some fifteen hundred feet more or less from the highway crossing, a signal setting mechanism *E* whose particular form, construction and operation is fully set forth in my pending application Serial #7,072, filed February 5, 1925, and allowed on February 21, 1925. This comprises, as illustrated in Figure 3, a rail-engaging bar, designated 10, mounted upon levers 11, these levers in turn being connected to a longitudinally shiftable bar 12, this bar being connected by a link 13 to a yoke 14. This yoke carries two longitudinally extending rods 15 which pass through a guide 16 and engage a collar 17 slidably mounted upon a longitudinally extending rod 18, in turn connected to a connecting rod 19. When the bar 10 is depressed in a direction to shift the lower ends of the levers 11 rearward, the rods 13, yoke 14, and the rods 15 are shifted forward and the collar 17 slides upon the rod 18 against the action of a spring 20 which bears against a shoulder 21 on this rod 18. This occurs only when a train is passing in a direction from right to left, but when a train is passing from left to right in Figure 3, the bar 10 will be depressed so as to carry the lower ends of the levers 11 toward the right in Figure 3, which will pull upon the rods 13, 14 and 15, and the collar 17 will engage against a shoulder 22 also on the rod 18 and will thus act to pull the rod 18 and with it the rod 19. Thus a train coming from the right in Figure 1^a toward the highway will act to pull on rod 19 and this will act to set the signal to danger position, as will more fully hereinafter appear.

This rod 19 extends toward the crossing or highway and at one point is provided with a slip joint 23 with which another section 19^a of the rod 19 engages. Thus upon a pull toward the right in Figure 1^a on this rod 19 the section 19^a will also be operated. This section 19^a extends beneath the highway *A* and is connected to the arm of a bell crank lever 24. This bell crank lever 24 is connected by a connecting rod 25 to the vertical arm of a bell crank lever 26, the horizontal arm of which extends parallel to a horizontal lever 27. This lever 27 has a transversely extending pin 27^a and the horizontal arm of the bell crank lever 26 rests upon this pin 27^a so that when the arm 25 is depressed by a pull on the connecting rod section 19^a the lever 27 will be depressed. This lever 27 is connected to a rod 28. This rod 28 in turn is operatively

connected to the crossing signal, as fully disclosed in my co-pending application filed of even date herewith above referred to, so that when the actuating device or setting mechanism above described has been engaged by a wheel of an oncoming train, engaging the bar 10 and depressing it, the signal will be set to danger, the signal being latched in this position, as fully described in said co-pending application. 75

Disposed on the other side of the lever 27 is a second bell crank lever 29 which also rests upon the pin 27^a and has a depending arm, which depending arm is connected to a rod 30 which extends to and is operatively connected with the bell crank lever 31, which in turn is connected to a longitudinally extending rod section 32 which is engaged with a slip joint 33 of the same character as the slip joint 23 heretofore described, and from this slip joint extends a rod section 34 which extends to one arm of a bell crank lever 35 (see Figure 1^a), the other arm of the bell crank lever being connected to a rod 36 which extends to one arm of a bell crank lever 37, the other arm of this bell crank lever being connected to a connecting rod 38 which extends beyond the switch *F* to a setting mechanism, designated generally *G*, of the same character as the setting mechanism *E*, only operating, of course, in the reverse direction, and which includes the bar 10 engaged by the wheels of the train, the levers 11, the rod 12, the link 13, the rods 14, and the spring 20 so that when a train comes from the left in Figure 1, it will actuate this setting mechanism and cause a pull upon the rod 32 to shift the signal mechanism so as to allow the signal to move from its safety to its danger position under the force of gravity, as described in the pending application. When the rod 32 has been pulled downward and the signal is raised to its danger position, the bar is latched, and when a train has passed beyond the crossing this latch is designed to be retracted, which permits the signal to return to its safety position under the action of gravity. 105

The restoring mechanisms for this purpose are designated *H* and *I* and will be described in connection with the restoring mechanism on the siding. The means whereby this restoring of the signal to its safety position is described is also fully described in my pending application Serial #7,072, filed February 5, 1925, as applied to the main line, but, as before stated, the present invention relates to the means whereby a train approaching the siding will actuate the signal and whereby a train on the siding will restore the signal to its safety position after the train has passed the highway and whereby a full train or a part of the train, if the train be broken in 115 120 125 130 135

backing, returning or moving off of the siding onto the main track, will again set the signal, and to this end I have provided a combination restoring and setting mechanism which will act to restore the signal to its safety position after the last car of the train on the siding has passed the highway crossing in either direction, but it will also act to reset the signal to its danger position if this train backs down upon the siding toward the crossing and only restores the signal to its safety position after this train, backing down the siding to get upon the main line, has passed the highway.

15 One of these combined restoring and setting mechanisms is illustrated in Figure 4. Taking the restoring mechanism which is on the right hand side of the highway and associated with the siding, it will be seen that it comprises a longitudinally extending bar 39, one end of which is inclined downward, this bar being mounted upon a plurality of bell crank levers 40 pivoted at 41 upon the rail. Mounted for longitudinal movement along the side of the rail is a longitudinally extending bar 42 having depending arms 43, to which the lower ends of the bell crank levers are connected. Thus it will be obvious that as the rail or bar 39 is depressed by the wheels of a train, the rod 42 will be shifted longitudinally. This rod at its end is pivotally connected to a yoke 44 having two parallel rods 45 carrying a cross piece 46 which slides upon a longitudinally extending rod 47 around which there is disposed a coiled compression spring 48. This rod 47 has upon it the shoulder or stop 49 against which the cross piece 46 abuts when the rods 45 move to the left in Figure 4, but when the rods 45 move to the right in Figure 4 the spring 48 will be compressed. The rod 42 is pivotally connected to a link 50 which is pivoted at the junction of the rod 42 with the yoke 44 and which extends away from the yoke and is pivotally connected to the lower end of a restoring lever 51, the upper end of which is formed with two angularly related faces, this restoring lever being operatively pivoted at 52 to the rail. The angular faces 53 and 53^a of the restoring lever are disposed so as to project slightly above the rail of the track.

It will now be seen that when a train moves from the left to the right and passes the highway crossing, the first wheels of the train will depress the bar 39, which will shift the rod 42 to the right in Figure 4, which will pull the restoring lever 51 down to a position so that its face 53^a is flush with the top of the rail. The push on the rod 42 will push the shoulder 46 and this shoulder 46 will simply slide upon the rod 47 and compress the spring 48 without in any way affecting the rod 47. Inasmuch as the bar

39 has a length equal to the longest distance between the inside trucks of a car and, of course, greater than the distance between the adjacent wheels of two cars, it is obvious that this bar 39 will remain depressed while the train is passing over it but as soon as the last wheel of the train has passed off the bar 39 the spring 48 will cause a reverse movement of the rod 42 and the restoring lever 51 will spring upward into the path of the last wheel and the last wheel, therefore, will rock the restoring lever over toward the right in Figure 4, pulling on the connecting rod 50, yoke 44, the rods 45, and the cross piece 46 will engage the shoulder 49 and pull the rod 47. This rod 47 is pivotally connected by a link 54 to a lever, which in turn is pivotally connected to a longitudinally extending rod 56 having a turnbuckle in its length, whereby the length of the rod may be adjusted, this rod 56 engaging with a bell crank lever 57, from one arm of which extends a transverse connecting rod 58 which extends beneath the main track.

The rod 58 is upwardly extended at 59, and passing through this extension 59 is a connecting rod 60 which, adjacent the track, is connected to a bell crank 61. This rod 60 has upon it a stop 62 which engages the upwardly turned end 59 of the rod 58. Therefore, it is obvious that when the rod 58 is pulled it will pull upon the rod 60. This rod at its end remote from the track is connected to the depending arm of a lever 63, the horizontal arm of which extends over transverse pins 64 carried by an arm 65, which in turn is connected to a rod 66 which is the means whereby the signal is lowered, as fully described in my pending application.

What is true with regard to the restoring mechanism H is equally true with regard to the restoring mechanism I, the same parts exactly being used, only reversed with relation to the parts of the restoring mechanism H, and this in turn is connected by a lever 55^a to a connecting rod 56^a to a bell crank 57^a, which bell crank is connected to a rod 58^a extending beneath the track, which rod is extended upward and engages with a shoulder 62^a on a connecting rod 60^a, which in turn connects with a bell crank 63^a operating on a transverse pin 64 of the lever 65 and thus upon the pull rod 66. Thus it will be obvious that when a train moves onto the siding from left to right that the wheels of the train simply depress the bar 39, thus depressing the restoring lever to the position shown and permitting the wheels to pass without affecting the restoring lever.

When, however, the wheels reach the restoring lever 51 of the mechanism H, they will act to depress the bar 39 of this mech-

anism H and to depress the restoring lever until the last wheel has passed off the bar 39. This will permit the restoring lever to spring upward and then the last wheel will force the restoring lever toward the right at the point H in Figure 1^a, which will cause a pull to be exerted upon the rod 47, which will pull on rod 56, which pull will be transmitted to rod 58 and thus to connecting rod 60, thence to the bell crank 63 to arm 65, which will pull down on the connection 66 and which will pull downward on the member which holds up the signal arm, permitting the signal arm to drop by gravity, as fully described in my co-pending application upon the signal before referred to.

It is also necessary that the restoring mechanism will act to set the crossing signal when the train, after it passes upon the siding, moves back toward the switch to pass back upon the main line. Thus, for instance, if a train enters the siding this train has heretofore set the signal to danger by means of the setting mechanism G. The train then enters upon the siding and passes over the restoring mechanism I. If the train has come from a distance and has passed the setting mechanism G, it will not affect the restoring mechanism I but if, for instance, the train is upon the main track between the setting mechanism G and the setting mechanism E and then this train passes onto the siding, it is obvious that some means must be provided for setting the signal as the train passes onto the siding, and under these circumstances the train entering the siding strikes the lever 51 and shifts this lever toward the right in Figure 1^a. The shifting of this lever 51 toward the right actuates a rod 67 by means of an angular bracket 68 which is mounted upon the rod 42. The rod 67 is connected to a bell crank lever 69 which is pivotally connected to a rod 70, this rod at its extremity being bent upward and having an aperture through which the rod 30 passes, the rod 30 carrying a shoulder 71 bearing against the turned-up end of the connecting rod 70. Thus when this rod 70 is pulled it will cause a pull upon the rod 30, which will pull upon the bell crank lever 29, causing a depression of the lever 27 and a consequent pull upon the rod 28 connecting to the latch, which will be open, permitting the signal arm to descend to its danger position.

If the train passes on across the highway and passes on beyond the restoring mechanism H, it will actuate the restoring lever 51 of this restoring mechanism and cause a pull upon the link 54, lever 55, rod 56, bell crank 57, rod 58, link 60, bell crank 63, lever 65, and rod 66, which will restore the signal to its normal or safety position. Meanwhile a train can pass on the main line and will

set the signal to danger as it approaches the highway and will restore the signal to its normal position as it leaves the highway by means of the restoring mechanism J connected to the main track. If, however, the train on the main line, while it goes beyond the restoring mechanism J, backs back again toward the left in Figure 1^a, the restoring mechanism J will set the signal once more to danger and the signal will not be set to safety position until the train reaches the restoring mechanism K, it being understood that the restoring mechanisms H, I, J and K are all of the same construction.

If the train on the side track passes beyond the restoring mechanism H, it will operate to restore the signal to a safety position, but if it then backs back across the highway the first wheels of the car will strike the restoring lever 51 of the restoring mechanism H and will set the signal to danger position, and then as the train reaches the restoring mechanism I the last wheels of the train will shift this restoring mechanism I over, and operating through the lever 65^a, the rod 56^a, the bell crank 57^a, the link 58^a and the rod 60^a will cause the restoration of the signal to its safety position.

It will be seen that a highway crossing signal constructed in accordance with the accompanying drawings and description and having a signal constructed in accordance either with my prior patent or with the signal which is illustrated in my pending application Serial #19,869 filed on the 31st day of March, 1925, and having actuating devices for setting and restoring the signal constructed in accordance with my application Serial #7,072, which was filed on February 5, 1925, will permit a train on the main line to set the signal to danger as it approaches the crossing and restore the signal to safety position after it has receded from the crossing a predetermined distance, which will not restore the signal to safety position unless the train has reached this distance or until the train has backed across the crossing and engaged a second restoring signal mechanism, and in which provision is made for the train to enter a siding, set the signal to danger position upon entering the siding, restore the signal to its safety position after the train on the siding has passed the crossing, reset the signal to its danger position if the train, after it has passed the crossing, returns or backs up, and again restores it to a safety position after the train has passed the crossing in its backing-up operation or which will permit the train to be divided and which will put the signal in safety position as soon as an effort is made to re-unite the train by moving one section toward the other, and that the action on the signal by the train on the siding is entirely independent of the action on the

125
130
135

- signal by a train on the main line, to the extent that if the signal has been cleared by the train on the siding, the train on the main line will set the signal to danger, but that
- 5 if the signal is at danger for any reason by a train on the siding it will remain at danger throughout the passage of a train on the main line until this train on the main line has cleared the crossing.
- 10 Inasmuch as the actuating means, that is, the restoring mechanism and the setting mechanism, have been fully illustrated and described in my pending application #7,072, it is not believed necessary that these
- 15 should be illustrated in detail and they are only shown diagrammatically. The same is true with regard to the signal per se which is shown in my co-pending application.

While I have illustrated a construction which I believe to be particularly effective, I do not wish to be limited to the details as it is obvious that these might be changed in many ways without departing from the spirit of the invention.

25 I claim:

1. In a highway crossing signaling system, a main track, a signal disposed beside the highway, train operated actuating means along the main track at each side of the highway and acting upon the approach of a train to set the signal to a danger position, train operated means associated with the main track located relatively adjacent the crossing for restoring the signal to safety position and operated by a train on the main track departing from the crossing, each restoring device being operated in one direction to restore the signal to safety position and the same restoring device being operable in the opposite direction to set the signal to danger if it has been previously set to safety.

2. In a highway crossing signal system, a main track and a siding, a signal disposed at the intersection of the highway with the main track and siding, train actuated means along the main track and disposed at a distance from the crossing on each side thereof and acting to set the signal to a danger position as a train approaches the crossing from either direction, train actuated means associated with the main track and located relatively adjacent the crossing without restoring the signal to safety position and operated by a train on the main track departing from the crossing, train actuated means disposed on each side of the crossing and relatively adjacent thereto for restoring the signal to safety position and operated by a train on the siding departing from the crossing in either direction, each restoring means on the main track and on the side track being operated by a train moving away from the crossing to restore the signal and being operated by a train

approaching the crossing to set the signal to danger if it has been previously set to safety.

3. In a highway crossing signaling system, a main track and a side track, a signal disposed adjacent the intersection of the highway with the main track and side track, train actuated means along the main track at a distance from the crossing and on each side thereof for setting the signal to a danger position on the approach of a train but each permitting the train to depart from the crossing without affecting the signal, train actuated means associated with the main track and located relatively adjacent the crossing operating to restore the signal to safety position when the last car of a train has passed the crossing, train actuated means associated with the siding and disposed on each side thereof acting to restore the signal to safety position as the last car of the train on the siding passes the crossing, each restoring means being operable in one direction by a train leaving the crossing to restore the signal to its safety position but being operable in the other direction by the first car of the train to set the signal to danger if it has previously been set to safety.

4. In a highway crossing signaling system, a main track and a side track, a signal disposed adjacent the intersection of the highway with the main track and side track, train actuated means along the main track at a distance from the crossing and on each side thereof for setting the signal to a danger position on the approach of a train but each permitting the train to depart from the crossing without affecting the signal, train actuated means associated with the main track and located relatively adjacent the crossing operating to restore the signal to safety position when the last car of a train has passed the crossing, train actuated means associated with the siding and disposed on each side thereof acting to restore the signal to safety position as the last car of the train on the siding passes the crossing, each restoring means being operable in one direction by a train leaving the crossing to restore the signal to its safety position but being operable in the other direction by the first car of the train to set the signal to danger if it has previously been set to safety, the restoring devices being so connected to the signal as to permit one restoring device to operate without affecting the other restoring device.

5. In a highway crossing signal system, a main track and a side track, a signal disposed adjacent the intersection of the highway with the main track and side track, train actuated means along the main track at a distance from the crossing and on each side thereof for setting the signal

6

to danger position on the approach of a train, mechanism permitting the train to depart from the crossing without affecting the signal, said mechanism including rectilinearly shiftable main signal setting rods, train actuated means associated with the main track and located relatively adjacent the crossing operating to restore the signal to safety position when the last car of the train has passed the crossing and including rectilinearly shiftable main signal restoring rods, train actuated means associated with the siding and disposed on each side thereof acting to restore the signal to safety position as the last car on the siding passes the crossing, each restoring means being operable in one direction by a train leaving the crossing to restore the signal to its safety position but being operable in the other direction by the first car of the train to set the signal to danger if it has

been previously set to safety and including rectilinearly shiftable rods having sliding operative connection in one direction with the main signal restoring rods but operating on said rods upon a pulling movement, brackets upon the rectilinearly shiftable rods of the siding, rods extending loosely through said brackets and having stops engaged by the brackets upon a movement of the siding restoring rods in one direction, said rods carrying the stops being operatively connected to the main signal restoring rods by a sliding connection in one direction, the main signal restoring rods having stops transmitting a pull exerted upon the rods passing through said brackets to the main signal setting rods. 25 30 35

In testimony whereof I hereunto affix my signature.

CARL R. GRAVES.
